STEREOTYPE FINISHING MACHINE

Christopher Verne Knell, Glen Ellyn, Ill., assignor
to The Goss Printing Press Company, Chicago,
Ill., a corporation of Illinois

Application November 16, 1945, Serial No. 629,122

6 Claims. (Cl. 90—15)

1

The present invention relates to a novel and improved plate finishing machine and more particularly to an improved machine for accurately finishing the interior of semi-cylindrical stereotypes such as are conventionally used for newspaper presses.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, deferred to herein and constituting a part hereof, illustrate one embodiment of the invention, and together with the description, serve to explain the principles of the invention.

Of the drawings:

Figure 1 is a side elevation, with certain parts broken away and other parts shown in section, of a typical and illustrative embodiment of the present invention;

Figure 2 is an end elevation of the plate finishing machine shown in Figure 1;

Figure 3 is a detail view of the upper portion of Figure 2 with certain parts omitted;

Figure 4 is a section along the broken line 4—4 of Figure 3;

Figure 5 is a view showing two positions of the plate as it is moved into the supporting arch for finishing;

Figure 6 is an end view of the rotary boring and slot milling means forming a part of the preferred form of the present invention;

Figure 7 is a side elevation, with certain parts being shown in section and a rotary boring means and slot milling means forming part of the preferred embodiment of the present invention;

Figure 8 is an end elevation of the tool head shown in Figure 7;

Figure 9 is a section along the line 9—9 of Figure 8;

Figure 10 is a detailed view, partly in section and with other parts broken away of the means for controlling the slot milling means of Figure 6;

Figure 11 is a top elevation of the milling cutter;

Figure 12 is a vertical section of the milling cutter housing and drive;

Figure 13 is a sectional view taken on the line 13—13 of Figure 12;

2

Figure 14 is a sectional view taken on the line 14—14 of Figure 15;

Figure 15 is a sectional view of a finished stereotype as produced by the finishing machine of the present invention, taken on the line 15—15 of Figure 14;

Figure 16 is a fragmentary sectional view showing the section 16—16 of Figure 17;

Figure 17 is a developed view of the interior surface of the plate prior to the plate being worked on by the finishing machine; and

Figure 18 is a sectional view taken on the line 18—18 of Figure 17 and showing the stereotype plate as it is received by the plate finishing machine.

The present invention has for its object the provision of a novel and improved stereotype plate finishing mechanism for accurately finishing the interior of a conventional semi-cylindrical stereotype without damaging its outer, or printing, surface. A further object is the provision of such a stereotype finishing machine in which the plate is accurately and firmly seated in a rigid form while the interior is surfaced and is automatically removed from the rigid form after the plate has been finished. The invention further provides a stereotype finishing machine which will accurately finish stereotypes which have been intentionally cast with a slightly smaller diameter than the diameter of the plate cylinder onto which they are to be mounted for printing, thereby providing a plate which more accurately fits the plate cylinder. Still another object is the provision of a novel and improved stereotype finishing machine for automatically forming recesses or cavities in the interior of the plates to adapt the stereotypes to be secured by tension to the plate cylinders.

In accordance with the present invention, the stereotype plate finishing machine includes an arch or hollow, generally semi-cylindrical form, of a diameter and length corresponding to the external dimensions of the stereotype after it has been mounted on the plate cylinder for printing, and means are provided below the arch or form for supporting the plate by engagement with its straight edges, with the axis of the stereotype parallel to the axis of the arch, and for moving one or both of the plate edge supporting means upwardly while moving one or both of them towards and then away from the other, thereby compressing the plate diametrically as it is raised into contact with the arch to seat it firmly therein, the movement of the supporting means away from each other being accomplished at the

end of the seating operation whereby scarring of the plate on the arch is avoided and the plate supporting members are removed from the path of the finishing tool which will accurately surface the interior of the plate. A further feature of the seating movement is that one side edge is seated first and contact of the plate with the arch flows up from this side edge and down to the other edge. The arch preferably has open ends whereby the plate may be positioned therein and removed therefrom by axial movement.

The plate seating means preferably comprises a lever means operated by rotatable cams which have a common actuating means, the lever means being provided at each side of the arch and including vertically slideable blocks on which the levers are pivotally mounted so that the levers may be horizontally swung as they and the blocks are vertically moved. One of the levers is preferably resiliently connected to its plate supporting means whereby the final seating of the plate is accomplished by a yielding action to accommodate minor dimensional variations in the plate.

Means are provided for finishing the interior of the plate and preferably comprise an axially movable cutter head or boring tool which is moved through the arch by means of a power driven screw, cam controlled milling cutters also being provided for cutting the plate hook recesses in the interior of the plate adjacent to its straight edges, as the interior of the plate is surfaced. These recesses are preferably spaced apart axially of the plate and are accurately located with respect to the plate hooks on the plate cylinder.

The finished plate is preferably removed from the arch or form in the same direction as it was inserted and a support or saddle is provided just behind the axially movable cutter head so that, on release of the plate from the arch, the plate is lowered onto the support and is moved out of the arch as the cutter head is screw returned to its original position.

The boring head described and illustrated herein is claimed in the co-pending application, Serial No. 629,123, filed November 16, 1945, of Curtis S. Crafts and Christopher Verne Knell, now Patent 2,604,017.

Referring now in detail to the accompanying drawings which illustrate a typical, illustrative and preferred embodiment of the present invention, there is provided an arch 23 or supporting member having a semicylindrical interior face of a diameter and length corresponding to the desired printing surface of the stereotype plate, and of sufficient strength so that it does not yield appreciably as the plate is firmly pressed into it and interiorly surfaced. Arch 23 comprises a heavily ribbed member which is bolted to the upper portions of the main frame 22, and is preferably located substantially midway between the longitudinal ends of the main frame, thereby providing a plate receiving portion at one end of the frame, and a plate delivering portion at the other end of the frame onto which the finished plate is delivered. In actual practice, said arch generally has a diameter of from sixteen to twenty inches and an axial length of from fifteen to twenty inches, the interior surface of the arch corresponding accurately to the printing surface of the stereotypes to be finished therein.

At the receiving end A of the plate finishing machine, at the left as shown in Figure 1 are provided a pair of spaced plate edge receiving surfaces 24 which may receive and support the

two straight, diametrically opposed edges of the stereotype 23 to be interiorly finished, axially aligned with the longitudinal axis of the machine.

Means are provided at the plate finishing portion B of the machine, intermediate its longitudinal ends for supporting the plate, which supports 25, 26 are normally aligned axially and laterally with the surfaces 24 and the plate may be slid from one to the other while the supports 25, 26 are in their normal or lowest position. Plate receiving surfaces 24 are fixed to the frame of the machine while surfaces 25, 26 are mounted for compound vertical and horizontal movement thereon independently of each other as more fully hereinafter described.

Plate supporting surfaces 24, 25 and 26 are preferably all in a single horizontal plane parallel to the diametral edges of the semi-cylindrical interior surface of the arch 23, so that the arch is uniformly spaced from the upper surface of the plate 23 at both sides thereof.

The supports 25, 26 are carried on plate rails 27, 28 slideable in lateral channels 29 formed in blocks 30, 31 which are slideable in vertical guideways 32 mounted on the main frame 22. Plate rails 27, 28 have depending portions with finished surfaces 33 engaging flats formed on the main frame 22. A threaded tie rod 34 ties block 31 to block 35 similarly slideable in guideway 32, whereby the distance between blocks 31 and 35 may be varied to accommodate stereoplates 23 of varying diameters. Block 30 is resiliently and adjustably connected to block 36 slideable in guideway 32 by means of threaded plunger 37 extending through both blocks and surrounded by coil spring 38 located in a stepped bore in block 30 and bearing upward against the latter and downward against nuts threaded on plunger 37.

Four cams 39 each comprise two cam tracks 40, 41. The tracks 40, seen in front elevation in Figure 3, act through rollers 42 journaled in blocks 35, 36, to raise the blocks upon revolution of the cams 39 from the illustrated position. Links 43 journaled in blocks 30, 31 carry fulcrum journals 44 of levers 45. Cam rollers 46 in tracks 41 shown in broken lines in Figure 3, upon the above-mentioned revolution of cams 39, oscillate with a horizontal directional component, the oscillation being transmitted over levers 45 to plate rails 27, 28 to which the levers are pivotally connected at 47, causing lateral travel of rails 27, 28 in channels 29.

For simultaneously and equally operating the cams 39, a pair usually being provided at each end of the plate 23, the cams are mounted on shafts 50 which are parallel and suitably journaled above the arch 20 and intergeared. As embodied, each shaft 50 has a gear 51 meshing with a mitre gear 52 on transverse shaft 53 journaled in the frame and provided with an operating lever 54 releasably coupled to the shaft 53 by means of set screw 55, so that a manual movement of the lever 54 can move cams 39 from their lowermost position to their uppermost position.

The two cams 39 connected to blocks 31 and 35 are designed to raise these blocks slightly ahead of blocks 30, 36, so that as the blocks 31, 35, carrying support 25 with them, reach the upper limit of their travel, blocks 30, 36 and support 25 have not yet reached their upper limit, all as clearly shown in Figures 3 and 5. These figures also show that the supports 25, 26, actuated by the above-described mechanism, have a compound motion which is upward and inward without tipping,

which is effective to compress plate 23 diametrically as it seats in arch 20 and thereby prevent any wiping action between plate and arch which would damage the printing surface of the plate. Subsequent to the full line position illustrated in Figure 5, support 25 is retracted laterally outward somewhat, which is effective to increase and equalize the diametrically outward seating pressure of the right edge of the plate in the arch. Contemporaneously with the lateral retraction of support 25, support 26 completes its upward travel and is laterally retracted. Completion of the upward travel of support 26 causes leftwardly successive peripheral portions of plate 23 to seat in the arch, the contact progressing upward from the right side of Figure 5 to the top of the arch and hence downward to the left edge which rests on support 26. It is notable that support 25 is positively actuated in its movement, while support 26 is resiliently actuated in its movement by mechanism which is similar to the actuating mechanism of support 25 except for the addition of spring 38, which is effective through support 26 to press plate 23 upward and cause the latter to exert circumferentially transmitted pressure against the positively actuated support 25. The right edge of plate 23 may be finished in register with its printing surface for color work or the like, and the above seating and clamping mechanism permits the entire plate to be seated in register with the registered right edge, so that the finishing of the interior and the forming therein of plate hook recesses for tension lockup of the plate on the printing cylinder may be done with unprecedented exactness of register.

While the plate is firmly secured in its position seated in the arch 20 it may be interiorly finished to conform accurately to the cylindrical surface of the plate cylinder of the printing press on which it will eventually be secured and printed. For this purpose, means axially movable of the plate are provided for boring or otherwise finishing the interior cylindrical surface of the plate, and due to the firm support of the plate this finishing may be much more accurate than usual; thereby resulting in a printing plate which will produce impressions of higher quality than usual.

To carry out this interior finishing of the plates, means are preferably provided for accurately boring the interior of the plate, such means moving axially of the plate as the boring tool is rapidly revolved.

Figures 16 to 18 show various views of the plate as it is placed on the finishing machine, while Figures 14 and 15 show schematic views of the plate, as finished.

The finished plate shown in Figures 14 and 15 comprises a semi-cylindrical member 60 having a printing surface 61 and an interior surface 62 to be seated on and closely conform to the outer surface of a plate cylinder and when so seated to provide a printing member of a predetermined size and having an accurate cylindrical surface so that the impression thereof will be of high quality.

Plate 60 is provided with internal recesses 63 between ribs 64, to lighten the plate, these ribs and recesses being shown more in detail in the developed view, Figure 17. Plate 60 is also formed with straight edges 65 of less thickness than the main body of the plate. Recesses 63 are formed over the entire inner surface, except at the edges, although shown only over a portion of the surface in Figure 17.

Figures 14 and 15 show the plate as it is fin-

75

ished by the machine illustrated (except that the ribbing is omitted for clarity). The interior surface of the plate 60 has been surfaced so that all of the ribs lie in a uniform cylindrical surface and the inner surface is formed with two parallel series of slots 66 closely adjacent the straight edges 65 each slot having a flat side 67 inclined towards the straight edge, the other longitudinal side 68 of the slot being part-cylindrical and terminating in rounded ends 69.

The means for interiorly finishing the stereotype comprise an axially movable rotary surfacing means, preferably a boring tool or cutter for surfacing the plate and axially movable controlled milling means for forming the longitudinal series of spaced slots, both means acting on the same axial movement of the finishing means. The finishing means also include means for radially pressing the plate against the arch immediately in advance and to the rear of the cutter means to insure accurate finishing of the plate. While many different forms of such means may be employed, I preferably provide the means illustrated and the frame 72 formed with slideways 70 parallel to each other and horizontally spaced running the greater part of the length of the machine on which the cutter means are mounted for movement axially of the plate 23. The cutter or boring means are carried by a slidable frame 72 having guides 73 which cooperate with the slideways 70.

Slidable frame 72 carries a heavy shaft 75 journaled therein and at one end is provided with a boring head 76 driven thereby and having a plurality of boring bits 77 extending radially therefrom and adjustable to bore the plate accurately to the proper diameter, the shaft 75 being accurately held in alignment with the axis of the arch 20. For accurately holding the plate 23 during the finishing and to exert pressure in addition to that exerted by the supporting means 25, 26, axially in advance and just behind the boring tool, the frame 72 is formed with two substantially semi-cylindrical plates 80, 80A respectively, somewhat smaller than the interior of the plate 23, one at either side of the boring head 76, each plate carrying a plurality of part-spherical rollers 81, spaced to contact with axially extending ribs 64 on the stereotype, each of said rollers being yieldably mounted by heavy springs 82 engaging pillow blocks 82A for radial movement relative to shaft 75 so that any irregularity in the surface of the plate 23 is smoothed out while the plate is finished. Plate 80A is formed integral with frame 72 and carries concentrically anti-friction bearing 75A of shaft 75, while plate 80 is removably mounted on frame 72 as by cap screws 80B.

The boring head is preferably driven at a high speed so that a fine finish is obtained on the interior of the plate. For this purpose, motor 90 is mounted at one side of frame 22 and drives longitudinal shaft 91 by belt 92 and suitable pulleys. Means are provided for driving shaft 75 from shaft 91, regardless of the axial position of boring head 76. Shaft 91 is formed to receive and drive slidably keyed or splined pulley 93 which is slidable on shaft 91 and is moved axially by bracket 94 depending from frame 72 and movable therewith. Pulley 93 by belt 95 drives pulley 96 on shaft 98 which carries pinion 97, journaled in frame 72, and meshing with gear 98 fast to shaft 75 and enclosed in housing 99.

Frame 72 is axially movable and may be mo-

tor driven. Motor 100 mounted on frame 22 is belted to pulley 101 carried by screw shaft 102 journalled in the frame 22 and in cooperating threaded engagement with a threaded sleeve 104 on frame 72 so that rotation of shaft 102 axially moves the frame 72 and its boring head 76 and pressure rollers 81. Motor 100 is reversible and may drive the frame 72 in either axial direction.

Limit switches 105 and 106 are provided in the motor circuit to prevent excessive axial movement of the boring head.

The milling cutters for milling the plate hook receiving slots in the interior surface of the plate 23 may be driven from the same motor 98 as the boring tool. Gear 93 drives pinions 108 on parallel shafts 112 which are mounted for rotation in and axial movement with frame 72. At its other end each shaft has a bevel gear 110 meshing with a bevel gear 114 on the milling cutter shaft 112 which is driven thereby to drive the milling cutters 113, while shaft 112 may oscillate about shaft 109 as the milling cutters 113 and chamfer milling cutters 113A on the same shaft and just below them are moved into and out of cutting contact with the plate surface as the slots 66 are formed.

Shaft 112 is mounted by bearings 114 in a housing 115 which has sleeve-like ends 116 concentric with shaft 109 and is mounted for oscillation by means of bearings 117, 118 seated in frame 72, while shaft 109 is rotatably mounted within one of the sleeves 116 by bearings 119. Thus milling cutters 113 may be rapidly rotated from motor 98 and may also be moved revolvably about shaft 109. In the full line position of Figure 6, the milling cutters 113 are rotating idly while in the dotted line position they are in cutting engagement with the plate 23 to form the slots 66 therein.

To control the length of the slots 66 formed in the plate 23, means are provided for rocking each of the milling cutters 113 towards and from the plate as the cutters are moved axially of the plate. The cutters 113 are mounted 45 for rocking motion by means of the sleeves 116, while the housing 115 is provided with a depending arm 120 pivotally connected to a slide 121 carrying a cam follower which is guided and controlled by stationary cam 124 fast to frame 23. Follower 122 is a roller mounted on a slide 121 which is connected to clevis 125 by screw rod 126, clevis 125 being pivoted to arm 120 by pivot pin 127.

Figure 10 shows the cam 124 having a slot forming track 130 and a return track 131 adapted to control follower roller 122 and thereby the rocking of the milling cutter 113. In its cutting the cutter frame 72 moves forward (downwards of the sheet in Fig. 10), follower 122 is moved laterally to form, for example, four slots 66 of the required depth and at the desired longitudinal points along the axial length of the plate 23. On reaching the end of the plate, follower 122 displaces switch 132 and enters the end of the cam track, switch 132 being then spring restored to the position shown. On reverse axial movement of the cutting and boring means, follower 122 travels in return track 131 until follower reaches star switch 133 which is rotated as the follower 122 enters the common cam track 135, switch 133 being held against retrograde movement by means of the detent spring 136, so that follower 122 always enters track 130 rather than the return track 131.

The pitch of lead screw 102 and the cut and speed of cutter bits 77 are so related that on one pass of the boring tool the interior of the plate is accurately finished, and simultaneously all of the plate hook recesses 66 are formed in the plate. Thereafter the boring tool and milling cutters may be idly withdrawn in the opposite axial direction.

When the interior of the plate has been fully finished, lever 54 may be returned to its original position dropping the plate to the lowermost position shown in Figure 5 so that it is free to be removed from the arch and the finishing machine. Means are preferably provided for automatically removing the plate from the arch on the return movement of the cutters, thereby making use of the otherwise idle axial movement thereof. To this end, frame 72 carries an arcuate saddle 140, preferably mounted on the gear housing 99 and shaped to fit the interior of the finished plate and at such a height that it, rather than the supporting ledges 25, 26 will support the plate as the cams 39 return the ledges to their normal inoperative position. The finished plate is thus deposited on the arcuate saddle 140 and when the axially movable frame 72 is returned to its original position the plate is carried with it to its unloading position C.

Suitable conventional switches are provided for:

Starting, stopping and reversing motor 100 driving the lead screw to cause the forward and reverse travel of the axially movable frame 72.

Starting and stopping the motor 98 for the boring and milling cutters.

Energizing signal devices such as signal lights for indicating that the plate is securely held for finishing, has been finished and that the finishing operation has been completed and the machine is ready to receive another plate.

By properly driving the various parts of the machine it is possible to finish stereotype plates at a rate well in excess of two plates per minute, depending on the skill of the operator.

The invention in its broader aspects is not limited to the specific mechanisms shown and described but departures may be made therefrom within the scope of the accompanying claims without departing from the principles of the invention and without sacrificing its chief advantages.

What is claimed is:

1. In a stereotype plate finishing machine comprising a substantially semi-cylindrical form to receive a plate, substantially vertical guideways mounted on said machine adjacent said form, blocks slidable in said guideways, said blocks being formed with channels, said channels extending laterally of said form, plate rails slidable in said channels, said plate rails being capacitated to support the straight edges of a plate in operative relationship to said form, levers mounted on said blocks and connected to said plate rails, and cam means connected to said blocks and to said levers and effective to lift said plate rails while moving them first inwardly then outwardly diametrically of said form.

2. A stereotype plate finishing machine as defined in claim 1 which includes milling means movable into cutting engagement with said plate for cutting axially-spaced tension lock-up pockets therein adjacent and parallel to the straight edges of the plate when said plate is supported in operative relationship to said form.

3. In a machine for finishing printing plates,

the combination comprising a concave generally semi-cylindrical form for receiving a plate, means providing a pair of generally vertical guideways adjacent said form on opposite sides thereof, a pair of blocks respectively slideable in said guideways, said blocks having respective generally horizontal guideways thereon, a pair of supporting members for supporting the opposite straight edges of the plate, said members being slidably engaged with said horizontal guideways respectively, a pair of generally vertical levers respectively pivoted on said blocks and having their lower ends connected to said supporting members, and a pair of cam means connected to said blocks and said levers for elevating said blocks and said supporting members while moving the latter horizontally along said horizontal guide ways first inwardly and then outwardly to clamp the plate against said form, one of said cam means being positively connected and the other yieldably connected to said blocks respectively.

4. A machine for finishing printing plates as defined in claim 3 which includes milling means movable into cutting engagement with said plate for cutting axially-spaced tension lock-up pockets therein adjacent and parallel to the straight edges of the plate when said plate is clamped against said form.

5. In a machine for finishing printing plates, the combination comprising a concave generally semi-cylindrical form for receiving a plate, means providing a pair of generally vertical guideways adjacent said form on opposite sides thereof, a pair of blocks respectively slideable in said guideways, said blocks having respective generally horizontal guideways thereon, a pair of supporting members for supporting the op-

posite straight edges of the plate, said members being slideable engaged with said horizontal guideways respectively, and means connected to said blocks and said supporting members for elevating said blocks and said supporting members while moving the latter horizontally along said horizontal guideways first inwardly and then outwardly to clamp the plate against said form.

10 6. A machine for finishing printing plates as
defined in claim 3 which includes milling means
movable into cutting engagement with said plate
for cutting axially-spaced tension lock-up pock-
ets therein adjacent and parallel to the straight
15 edges of the plate when said plate is clamped
against said form.
